UNITED STATES PATENT OFFICE.

FRED L. FULCER AND RAYMOND J. RITGER, OF HORTONVILLE, WISCONSIN.

SNOWPLOW.

Application filed April 4, 1924. Serial No. 704,177.

To all whom it may concern:

Be it known that we, FRED L. FULCER and RAYMOND J. RITGER, citizens of the United States, residing at Hortonville, in the county 5 of Outagamie and State of Wisconsin, have invented certain new and useful Improvements in Snowplows, of which the following is a specification.

This invention relates to new and useful 10 improvements in snow plows and has for its principal object to provide an efficient means for removing snow from the road surface.

One of the important objects of the 15 present invention is to provide a snow plow wherein means is associated therewith for conveying the snow removed from the surface of the road by the scoop to a blower, means being further associated on the snow 20 plow for breaking up the lumps of snow before the same reaches the blower.

A further object of the invention is to provide a snow plow wherein the several parts thereof are adapted to be actuated 25 simultaneously, means being further provided for disconnecting the further operation of the several elements whenever desired.

A still further object of the invention is 30 to provide a snow plow of the above mentioned character, which is simple in construction, inexpensive, strong and durable, and further well adapted for the purposes for which it is designated.

Other objects and advantages of this 35 invention will become apparent during the course of the following description.

In the accompanying drawings forming a part of our specification and in which like 40 numerals designate like parts throughout the same,

Figure 1 is a top plan view of my improved snow plow with the blower extension pipe removed,

Figure 2 is a longitudinal sectional view 45 therethrough,

Figure 3 is a detail view of the blower casing with the fan mounted therein,

Figure 4 is a top plan view of a steering 50 mechanism forming a part of the present invention, and

Figure 5 is a side elevation thereof.

In the drawings wherein for the purpose of illustration is shown the preferred embodiment of our invention, the numeral 1 55 designates generally the frame upon the rear end of which is supported a power plant 2 of any well known construction. The purpose of this power plant will herein-after be more fully described. The forward 60 portion of the frame 1 is inclined as shown at 3 in the drawings with reference more particularly to Figure 2, and the lower outer edge of the forward portion of the frame 1 has mounted thereon a transversely 65 extending scoop 4 which is supported in close proximity to the surface of the road or ground over which the snow plow travels when in use. The rear portion of the frame 1 is further supported on the wheeled truck 70 5 whereby the plow may be easily transported from place to place and connected to the rear end of the plow is the hitch 6 which provides a means for connection to the draft device adapted to be connected to 75 the plow such as a tractor.

Extending transversely between the sides of the inclined portion 3 of the frame, adjacent the upper edge of the scoop 4 and the upper portion of the inclined frame 3, 80 are the shafts 7 and 8 respectively, suitable sprocket wheels, such as are shown at 9, being provided on the shafts 7 and 8 adjacent the inner sides of the inclined portion 3. Adapted to travel over the sprocket wheels 85 on the shafts 7 and 8 respectively, are the sprocket chains 10 and between which extend the endless conveyor belt 11. Arranged transversely on the conveyor belt 11 at spaced intervals are the flanges 12, the purpose of which will also be hereinafter more fully described. The sides of the inclined portion 3 of the frame are provided with the upstanding side walls 13 which co-operate with the side portions 14 associated 90 with the scoop 4 for preventing the snow from accidentally falling off of the conveyor before the same is delivered to the blower.

Extending upwardly from the upper portion of the inclined portion 3 of the frame 1 on the side thereof, are the vertical stand-

ards 15. Extending transversely across the frame 1 and having ends journalled in the extending brackets or standards 15, is the transverse shaft 16 and upon which are 5 mounted or otherwise fastened thereto, the beaters 17, the same preferably being in the form of blades, such as is clearly shown in Figure 2 of the drawings, and any number of these beaters may be provided on the 10 shafts as is deemed necessary and are furthermore arranged in proper spaced relation with each other in the manner as shown in Figure 1. The beaters 17 on the shaft 16 are preferably arranged directly above the 15 upper portion of the endless belt or conveyor, and are adapted to cooperate therewith. Adapted to extend over the beaters 17 and supported by the frame 1, is the hood 18.

20 Supported on the frame 1 between the sides thereof and arranged directly in rear of the endless conveyor and beater, is the blower casing 19. The bottom of the casing 19 is preferably closed, while the upper portion thereof converges toward the central portion and terminates into an outlet pipe 20, in the manner as clearly shown in Figure 3 of the drawings. The rear wall of the casing 19 is closed as shown at 21, while the 25 front wall or the wall adjacent the endless conveyor or beater, has its major portion open, as is shown at 22. Supported in the casing 19, are the pair of rotary blades or fans 23 and 24 respectively, and these bands 30 are preferably supported on the shafts 25 and 26 which extend through the rear wall 21 of the casing 19 and are journalled in a suitable manner in the transversely extending braces 27 which are supported between 35 the sides of the frame 1. Extending upwardly from the bottom of the front wall of the casing 19 and communicating with the upper end of the conveyor belt 11 is the pan or hopper 28. The hopper 28 is preferably 40 inclined in the manner as shown in Figure 2 of the drawings, and is adapted to cooperate with the conveyor belt and the beater 17 mounted on the shaft 16 and in the manner hereinafter to be more fully described.

45 For the purpose of actuating the conveyor belt, the beater shaft 16 upon which the beater 17 is mounted and the rotary fans 23 and 24 respectively, simultaneously, we provide a suitable gearing which is connected up with the power plant 2 in the manner 50 to be presently described. The rear end of the shafts 25 and 26 respectively, which support the rotary blades or fans 23 and 24 respectively, have bevelled gears 29 and 30 secured respectively thereon. These bevelled gears are adapted to mesh with the bevelled gears 31 and 32 respectively, supported on the transversely extending shaft 33. The 55 shaft 33 is preferably supported by means of the brackets 34, the latter being arranged on

the transversely extending braces extending across the frame 1 in the manner as shown in Figure 1 of the drawings. An additional bevelled gear 35 is carried by the intermediate portion of the transverse shaft 33 70 and is adapted to mesh with a bevelled gear 36 mounted on the forward end of the drive shaft 37. This drive shaft 37 is adapted to be driven by the drive shaft of the power plant 2 in the manner well known in the art 75 and for the purpose of disconnecting the bevelled gear 36 from engagement with the bevelled gear 35, we provide the clutch lever 38. The construction above described provides a means for rotating the rotary fans 80 23 and 24 mounted in the casing 19 in opposite directions whereby the fans will efficiently and positively discharge the snow delivered into the casing out through the discharge pipe 20.

85 The outer end of the transverse shaft 33 extends through the side rail of the frame 1 and has mounted thereon a bevelled gear 39. Supported in any suitable manner on the aforementioned side rail of the frame 1, is 90 the longitudinally extending shaft 40. The brackets 41 are provided for holding the shaft 40 in position on the frame. The rear end of the shaft 40 has a bevelled gear 42 mounted thereon which is adapted to 95 mesh with the bevelled gear 39 mounted on the outer end of the transverse shaft 33. The opposite end of the shaft 40 has the worm gear 43 provided thereon and this worm gear meshes with the gear wheel 44 100 mounted on the outer end of the shaft 8 which supports the upper portion of the endless conveyor belt 11. This construction provides a means whereby the endless conveyor may be actuated through the medium 105 of the gearing and the drive shaft of the power plant 2.

110 For the purpose of actuating the beater shaft 16 upon which the beaters 17 are supported, we provide the shaft 16 with a suitable sprocket wheel 45 which is in alignment 115 with the sprocket wheel 46 supported on the shaft 47. The latter extends through the frame having a bevelled gear 48 mounted on the outer end thereof adapted to mesh with a similar bevelled gear 49 provided on the intermediate portion of the shaft 40. A sprocket chain 50 is trained over the alining sprocket wheels 45 and 46 respectively, and it will thus be seen that the endless conveyor, 120 the beater shaft with the beaters thereon and the rotary fans will all be simultaneously actuated when the drive shaft of the power plant is connected to the drive shaft 37 and whereby the shafts 33 and 40 and the 125 gearings mounted thereon will rotate. In operation, the snow plow is adapted to travel over the road covered with snow and as the plow moves in the direction indicated by the arrow, the scoop 4 will cause the snow on 130

the road to be delivered onto the endless conveyor belt 11 and with the conveyor belt, the beater shaft and rotary fans in operation, the snow delivered to the conveyor belt 5 will be carried upwardly on the frame and will be deposited into the pan or hopper 38 whereby suction from the fans 23 and 24 will cause the snow to be drawn up into the casing and will be discharged outwardly 10 through the discharge pipe 20 on the sides of the road. The purpose of the beater shaft 16 and the beaters 17 mounted thereon is to provide a means for breaking up the heavy lumps of snow before the same reach 15 the blower fans and will thereby prevent any possibility of the snow from being accidentally discharged back onto the road from which it has been scraped. The snow plow will be moved along the ground until 20 all of the snow has been scraped therefrom by the scoop 4 and the side walls 13 will prevent the possibility of the snow delivered to the endless conveyor from being discharged laterally from the frame previous to the 25 same being delivered to the blower fan. In this manner, a road or any other surface may be readily cleaned from snow in an efficient manner and at a very low cost.

In Figures 4 and 5 of the drawings, we 30 have shown a steering means which is adapted to be associated with the rear end of the frame 1 and the same comprises the supporting base 51 upon which is supported the vertical shaft 52, the latter being arranged centrally thereon. The upper end of the shaft 52 extends through a suitable plate 35 53 which is supported by means of the brackets 54 and has mounted on its upper end the gear wheel 55 which cooperates with the worm gear 56 mounted on the shaft 57 which is journalled in suitable brackets 58 supported on the plate 53 and the brackets 40 54 respectively, and on the outer end of which is the operating handle 59. Mounted 45 on the vertical shaft 52 between the plates 53 and the supporting base 51 is the drum 60. Steering cables such as are shown at 50 61 and 62 in the drawings are connected at their forward ends to the lower portion of the inclined portion 3 of the frame 1 as shown at 63 in the drawings and extend along the sides of the frame and through the guides 64 supported laterally on the sides 55 of the frame, the rear ends of the cables extending around suitable pulley wheels 65 supported on the ends of the supporting base 51 and are connected to the drum 60. The operator of the snow plow may thus enable the same to be steered during its trans- 60 portation by actuating the handle 59 in either direction, in the manner as is well known in the art, and a further description of the same is not thought necessary.

For the purpose of further breaking the 65 lumps of snow as the scoop comes in con-

tact with the snow, teeth such as are shown at 4' are provided on the scoop 4 extend outwardly therefrom as is clearly shown in Figures 2 and 3 of the drawings. Supported on the outlet pipe 20 of the blower 70 casing 19 and adapted for rotary movement thereon is the blower extension pipe or spout 66. The outer end of the spout is provided with an adjustable cap 67 for permitting the operator to direct the discharge 75 of the snow from the spout. A cable 68 is secured to the cap 67 and is attached to the upper forward portion of a handle 69. The handle 69 is carried by the spout 66 and extends outwardly therefrom in the manner 80 as clearly illustrated in Figure 2 of the drawings. The outer portion of the handle has a weight 70 to balance and support the spout on the upper end of the blower pipe.

The provision of a spout and handle 85 therefore enables the snow to be discharged on opposite sides of the snow plow, or if desired may be deposited into a wagon traveling along the side of the snow plow. The handle facilitates the turning of the spout 90 in any direction described.

The simplicity of our snow plow enables the same to be easily and quickly placed in an operative position and does not require the employment of a considerable number of 95 men in order to operate the several parts of the plow. A snow plow of the character above described may further be manufactured at a very low cost and will also be strong and durable.

While we have shown the preferred embodiment of our invention, it is to be understood that various changes in the size, shape and arrangement of parts may be resorted to without departing from the spirit of the 105 invention and the scope of the appended claims.

Having thus described our invention, what we claim is:

1. A snow plow comprising a frame, a hopper mounted thereon, ejectors mounted in the hopper for removing the snow therefrom, an inclined elevator arranged to deliver the snow into the hopper, cutters located in advance of the elevator, and beaters 110 located above the delivery end of the elevator and the receiving edge of the hopper, and adapted to reduce the volume of snow which is elevated by the elevator into strips 115 as it passes into the hopper.

2. A snow plow including a frame, a hopper mounted thereon, ejectors mounted in the hopper for removing the snow therefrom, an inclined elevator arranged to deliver the snow into the hopper, side walls rising above the elevator, cutters located in advance of the elevator, and beaters located above the delivery end of the elevator and the receiving edge of the hopper adapted 125 to reduce the volume of snow which is de- 130

livered by the elevator into strips as it passes into the hopper for engagement with the ejectors.

3. In combination, a platform adapted to be mounted on a truck or the like, pulleys at the ends of the platform, a drum at the intermediate portion of the platform, means for rotating the drum, a snow plow, a pair

of cables attached to the front end of the snow plow and trained rearwardly along 10 its sides and over the pulleys and attached to the drum and coiled thereabout.

In testimony whereof we affix our signatures.

FRED L. FULCER.
RAYMOND J. RITGER.
